UNITED STATES PATENT OFFICE.

WILLIAM TYREE, OF CHRISTCHURCH, NEW ZEALAND.

APPARATUS FOR TEACHING WRITING.

SPECIFICATION forming part of Letters Patent No. 592,029, dated October 19, 1897.

Application filed August 7, 1895. Serial No. 558,488. (No model.)

To all whom it may concern:

Be it known that I, WILLIAM TYREE, a citizen of New Zealand, residing at 71 Cathedral Square, Christchurch, in the provincial district of Canterbury, New Zealand, have invented new and useful Improvements in Apparatus for Use in Teaching Writing, of which the following is a specification.

In teaching writing it is the common practice to employ manuscript copying-books having a printed head-line at the top of the page. In practice this is found objectionable, as in writing each succeeding line the scholar is liable to imitate his own handwriting in the preceding line instead of imitating the head-line.

Now this invention provides a simple apparatus for use in connection with copy-books whereby the head-line which the scholar is desired to copy may be moved down from line to line as he proceeds.

It consists of a light case one side of which forms a frame through which the copy or head-line is displayed. The case serves as a receptacle for a number of such copies, which may be substituted for each other as desired. It may also serve as a receptacle for pencils, pens, or other implements. It can be used as a ruler for ruling lines, and is provided on one or more of its sides with a pad of blotting material. The shape of the frame maintains the copy in a sloping position, making it more readily visible to the scholar.

Referring to the accompanying drawings, Figure 1 is a perspective view illustrating my invention in use on a copy-book. Fig. 2 is a perspective view of the apparatus drawn to a larger scale; Fig. 3, an inverted plan showing clips for securing blotting material; Fig. 4, a transverse section on line 4-4, Fig. 2.

Similar letters of reference apply to the same parts in all the figures.

The case *a* is preferably made of thin sheet metal and preferably of approximately triangular form. The side *b* has hinges *d* connecting it to the side *e* of the casing and is made with an opening through which a copy-line is displayed.

The copy-lines are written or printed upon thin strips of cardboard or other material *c*,

a number of such strips being packed upon each other within the case.

If desirable, the case may also be divided by a partition *e* to form a receptacle *a'* for pens or pencils, a door *h*, having hinges *j*, being provided in one end of the casing through which they may be inserted and extracted. 55

A pad of blotting-paper *g* may be attached to the bottom of the casing by the flat spring-clips *i* of brass or other metal soldered to the casing *a*, so that in moving the case down the line upon which it is placed is effectually blotted. 60

The lower edge *k* of the side *e* is made true, so that it may serve as a ruler. 65

In operation when it is desired to use a copy the required strip is selected from the pack and placed upon the top of the others, so as to be visible through the frame, which when a hinged frame is used is then closed. 70

The case may then be placed in a convenient position upon the manuscript book and moved down as the scholar proceeds with his task.

It will be evident that instead of using a hinged frame having an opening through which the copy is displayed it would be easy to use a slip of glass fixed or arranged to slide in guides or grooves formed with or upon the sides of the case. The door *h* would then occupy the whole of one end of the case, so that the slips might be withdrawn as described. 75 80

What I claim as my invention, and desire to secure by Letters Patent, is—

The apparatus for use in teaching writing 85 consisting of the case *a* divided longitudinally by the plate *e* forming a compartment for the reception of writing-copies *c* and a compartment *a'* for writing implements, the door *h* having hinges *j* giving access to the compartment *a'*, and the side *b*, having hinges *d*, giving access to the copies *c* the said side being provided with a longitudinal opening through which the uppermost copy is visible substantially as specified and illustrated. 90

Dated the 9th day of July, 1895.

WILLIAM TYREE.
